[57] CLAIM

The ornamental design for a vehicle window unit exterior surface, as shown and described.

DESCRIPTION

FIG. 1 is a front perspective view of the vehicle window unit exterior surface, showing my new design;
FIG. 2 is a front elevation view of a vehicle window unit exterior surface showing a second embodiment of
my new design drawn to an enlarged scale the sole
difference being that it is for the opposite side of the
vehicle shown in FIG. 1; and,
FIG. 3 is an enlarged front elevation view of the unit
shown in FIG. 1.

FIG. 1

FIG. 2

FIG. 3
